UNITED STATES PATENT OFFICE.

AUGUSTE ARTHUR CAILLE, OF DETROIT, MICHIGAN.

PRINTING OR EMBOSSED MACHINE.

SPECIFICATION forming part of Letters Patent No. 783,927, dated February 28, 1905.

Application filed November 1, 1902. Serial No. 129,642.

To all whom it may concern:

Be it known that I, AUGUSTE ARTHUR CAILLE, a citizen of the United States, residing at Detroit, in the county of Wayne and 5 State of Michigan, have invented certain new and useful Improvements in Printing or Embossing Machines, of which the following is a specification, reference being had therein to the accompanying drawings.

- 10 The invention relates to printing or embossing machines, and more particularly to that class in which a multiple of characters may be independently selected and successively printed or embossed on a strip.
- 15 The invention consists in the peculiar construction and arrangement of parts, as herein-after described and claimed.

In the drawings, Figure 1 is a vertical longitudinal section through the machine. Fig. 2 is an elevation of the mechanism shown in section in Fig. 1. Fig. 3 is an elevation of the same mechanism viewed from the opposite side. Fig. 4 is an enlarged section substantially on line *x* *x*, Fig. 1. Fig. 5 is a horizontal section substantially upon line *y* *y*, Fig. 1, but showing the parts secured to the carriage in plan. Fig. 6 is a front elevation of the wheels carrying the embossing-dies.

Generally described the machine comprises 30 a series of dies or type characters from which any one may be selected and registered with the work, also feed mechanism for feeding the material which is to be printed or embossed into registration with the selected die, 35 and coin-controlled mechanism by which the machine is normally locked from operation and when unlocked by the insertion of a coin is capable of only a limited number of actuations. The machine therefore comprises three 40 main groups of instrumentalities, the first comprising a mechanism by which the proper characters are selected and by which the dies are caused to operate upon the work, the second the feed mechanism, and the third the 45 coin-controlled mechanism. Each of these main groups contains subgroups of coating elements, and the elements of the main groups are also interrelated, so as to perform combined functions. In describing the mechanism I will, however, first separately describe

the mechanism constituting the main groups and subsequently describe the interrelation of parts.

The printing or embossing mechanism comprises two members carrying, respectively, corresponding male and female dies and movable so that any selected character may be registered with the work. As preferably constructed these dies are formed upon wheels or disks 1 and 2, respectively, mounted upon shafts 3 and 4. The shaft 3 is journaled in stationary bearings upon suitable framework, such as 5, while the shaft 4 is journaled in movable bearings, which permit of moving the wheel 2 in or out of peripheral contact with the wheel 1. For effecting this movement suitable mechanism is provided, such as shown, which consists of toggle-levers, comprising links 6 and 7, pivotally connected to each other and the former pivoted at 8 to the frame 5. The link 7 is pivotally connected to a bearing 9, which is slidably secured in guides upon the frame 5 and is connected by an arm 10 with the bearing 11, pivotally secured at 12 to the frame 5. The arrangement of the toggle-lever is such that when the links 6 and 7 are moved into alignment the bearing 9 will be moved in a position to carry the wheel 2 into peripheral contact with the wheel 1. To permit of accurate adjustment, the link 6 is preferably made extensible by forming it in three sections, the intermediate section 13 having a right and left threaded engagement, respectively, with the end sections. For actuating the toggle a rock-shaft 14 is journaled in the frame and provided with a cam or rock-arm 15, adapted in the rotation to bear against the knuckle-joint of the toggle-lever to straighten out the links 6 and 7.

The individual dies or type characters which are to be embossed are secured to the peripheries of the wheels 1 and 2. As shown, the male dies 16 are detachably secured to the wheel 1 by being formed upon blocks or plates 17 having a dovetail engagement with corresponding recesses in the periphery of the wheel. This construction permits of removing and replacing any individual character when necessary. The female dies may, if

desired, be correspondingly attached to the wheel 2, but preferably these are formed directly in the periphery of the wheel. For causing the corresponding male and female dies to register, the shafts 3 and 4 are geared together, as by the sprockets 17 and 18 and chain 19. The shaft 3 is also provided at its forward end with a handle or knob 20, by means of which it may be rotated. The position of the dies is indicated by means of the dial 21, having placed thereon a series of characters corresponding to the dies, and an index 22 is arranged in proximity to this dial. The arrangement is such that whenever the dial is turned to register the proper character with the index a corresponding character in both male and female dies will be registered with the work.

The mechanism thus far described is all enclosed within a suitable casing 23, in the front of which is an opening for exhibiting the dial 21 and for access to the handle 20. The shaft 14 also projects outward through the side of the casing and is provided with an operating crank-handle 24.

The mechanism constituting the second group includes the parts used in feeding the blank. The latter is preferably in the form of a thin and comparatively narrow ribbon, of metal or other suitable substance, which in the operation of the machine is inserted between the registering corresponding male and female dies on the wheels 1 and 2 and is embossed thereby. The means employed for feeding this ribbon comprise a feed-roll and mechanism actuated by the rock-shaft 14 for periodically rotating said roll to cause the feeding of the blank. In the construction shown a pair of feed-rolls 25 26 are arranged in proximity to each other and upon opposite sides of the plane of feed. These rolls are journaled in bearings upon the reciprocating carriage 27, which during the operation of the machine is adapted to be moved toward or from the wheels 1 and 2. The carriage 27 is slidingly secured to the frame 5 by means of lugs or bearings 28 and 29 and 30 engaging with corresponding ways 31 and 32 and 33 upon the frame 5. The rolls are yieldingly pressed together preferably by journaling the roll 25 in the pivotal arm 34, which is pressed downward by the tension of the spring 35. The rolls are also connected to each other by means of intermeshing gears 36 and 37, respectively, secured thereto. The roll 26 is sleeved upon the shaft 38, journaled in bearings upon the carriage 27 and extending upon opposite sides thereof and of the frame 5. At one end of this shaft is a crank-disk 39, sleeved thereon and connected to the gear 37. This disk is connected by a link 40 with a rock-arm 41, the latter being pivoted at 42 to the frame 5. Thus when the carriage 27 is reciprocated the shaft 38 and disk 39 will be carried therewith and through the connecting-

link 40 will impart a rocking movement to the arm 41. This arm is provided with a projecting lug 43, which in the movement of the arm will be carried into proximity to the wheel 1.

44 represents stops arranged upon the wheel 1 and corresponding to each of the type characters thereon. These stops are so arranged that whenever the male and female dies of a particular character are in registration the corresponding stop 44 will extend in the path of the lug 43 on the arm 41 and will thereby arrest the rocking movement of the arm 41.

The disk 39 is also connected by a link 45 with a lever 46, pivotally secured to the frame. The free end of this lever extends into the path of a lug 47 upon the rock-arm 48, secured to the shaft 14. The arrangement of the parts is such that when in the movement of the shaft 14 the lug 47 strikes against the lever 46 it will impart a slight rocking movement thereto, which through the link 45 will impart a rotary movement to the disk 39. This rotation of the disk continues until the lug 43 engages with a stop 44. To provide for the further movement of the lever 46 after the engagement of the lug 43 with the stop 44, the link 45 is yieldingly connected to the lever 46 by a spring 49. Thus when the movement of the disk 39 is arrested the lever 46 is still free to continue its movement under the actuation of the lug 47.

From the description above given it will be understood that the rocking movement of the shaft 14 will impart a rotary movement to the disk 39 and through the latter to the gears 36 and 37 and feed-rolls 25 and 26. It will be further understood that the amount of this movement is variable and is determined by the position of the particular stop 44 which is in the path of the lug 43. Thus for some characters occupying a small space the corresponding stop 44 is of sufficient length to arrest the lug 43 after a slight movement only has been imparted to the feed-rolls. For other characters requiring more space a greater movement is imparted to the disk and rolls before the lug 43 engages with the stop 44.

As has been previously stated, the rolls 25 and 26 are journaled in bearings on the reciprocating carriage 27. The latter also derives its movement from the rock-shaft 14 through the following mechanism: 50 is a lever fulcrumed on the frame 5, one end of said lever extending into proximity to the bearing 51 on the carriage 27 and the other end extending into adjacency to a cam 53 on the shaft 14. This cam 53 is so proportioned and timed that it will actuate the lever 50 in the initial rocking movement of the shaft 14 and before the lug 47 engages with the lever 46. The result will be that the carriage 27 will be moved toward the embossing-wheels and will complete its movement before rotary movement is imparted to the feed-rolls carried thereby. The object of this reciprocating movement is

to facilitate the severing of the unembossed from the embossed portion of the strip after the embossing operation has been completed. This function is performed in coöperation with 5 cutting-off dies upon the embossing-wheels, which are to be more fully hereinafter described. Another object of the reciprocating carriage is to assist in the operation of the coin-controlled mechanism, and a third function is that it exactly registers the dies in the manner hereinafter described.

The mechanism of the last general group comprises the parts controlling the operation of mechanism already described and which in 15 turn are coin-controlled.

54 is a coin-chute into which the coin may be conducted from the opening in the top of the casing into its operating position. Below the discharge end of the chute is normally 20 arranged a coin-support 55, which serves to temporarily support the coin at the lower end of the chute. Just above this support the chute is cut away upon opposite sides to form an opening for the passage of the finger 56 therethrough, said passage being, however, closed whenever the coin is in the chute. The finger 56 is secured to a rock-shaft 57, journaled in the frame and having a crank-arm 58 thereon. This crank-arm is connected to the 30 rod or link 59, extending downward therefrom and normally resting upon the lug 47 on the rock-arm 48 when the latter is in its initial position.

60 is a pivoted hooked arm or dog connected by the link 61 to the link 59.

62 is a lug for coacting with the hooked dog 60, said lug being formed upon either the arm 48 or other member secured to the shaft 14.

The parts just described are adapted to prevent the actuation of the machine excepting when the coin is in place at the lower end of the chute 54 and supported upon the member 55. The locking is effected by the dropping of the dog 60 into engagement with the coacting lug 62 whenever the lug 47 is lowered by the initial movement of the shaft 14. The amount of movement necessary to effect the locking is very slight and is accomplished before any of the mechanism actuated by the 45 shaft 14 is operated. When, however, a coin is placed in the chute 54, the rod 59 is held from downward movement by reason of the engagement of the finger 56 with the coin in the chute and the consequent holding of the 50 rock-shaft 57 and crank-arm 58 from movement. Thus the dog 60 will be held in a position where its hook is out of the path of the lug 62, and the rotation of the shaft 14 is thereby permitted.

60 Whenever the machine is unlocked by the insertion of a coin in the chute 54, the mechanism will be free to be actuated successively until a predetermined number of characters have been embossed. To then arrest further 65 movement of the machine, mechanism is pro-

vided for throwing out the coin, so as to permit the finger 56 to freely move, and thereby again lock the shaft 14 from operation. This mechanism is of the following construction: 63 is a ratchet-wheel secured to the shaft 38, 70 preferably upon the opposite side of the frame from that on which the disk 39 is arranged. 64 is a pawl for engaging the ratchet-wheel 63, which pawl is carried by the arm or rod 65. The latter is connected at its lower end to a lever 66, which is fulcrumed upon the frame 5 and extends with its free end into proximity to the cam 67 on the shaft 14. The cam 67 is proportioned and timed to impart a movement to the lever 66 whenever the shaft 14 is 80 rocked, said lever in turn lifting the rod 65 and causing the pawl 64 to actuate the ratchet-wheel 63. The rotation of the ratchet-wheel 63 will impart a similar movement to the shaft 38; but its movement is resisted by the tension 85 of a spring 68, said spring, as shown, being connected to a rock-arm 69 upon the opposite end of the shaft 38. Each operation of the shaft 14 will cause the actuation of the pawl 64 and ratchet-wheel 63, so as to move the latter 90 one notch. To prevent it from being immediately returned by the spring 68, the dog 69^a is arranged to engage with the ratchet-wheel, and this dog is controlled by the position of the coin-support 55. As shown, said coin-support 95 and dog are formed upon opposite ends of the lever 70, which is pivotally secured to the frame. To relock the mechanism after a definite number of actuations, the coin-support 55 is withdrawn from beneath the chute 54, 100 so as to permit of the disengagement of the coin therefrom, and at the same time the dog 69^a is disengaged from the ratchet-wheel 63 to permit the latter to return to its initial position, these movements being effected by the 105 following construction of mechanism: 71 is a pin upon the ratchet-wheel 63, and 72 is a lever fulcrumed upon the frame and extending in proximity to the ratchet-wheel. This lever has formed at one end thereof a seat 73, 110 against which the pin 71 bears when the ratchet-wheel is in its initial position. The lever 72 is in the form of a bell-crank and has its opposite arm connected by a link 74 with the lever 70 upon one side of its fulcrum. The arrangement is such that when in the rotation of the ratchet-wheel 63 the pin 71 has almost completed a revolution it will bear against the opposite side of the lever 72 and cause the actuation of the latter. This 115 through the connecting-link 74 will cause a movement of the lever 70, said movement being sufficient to completely withdraw the coin-support 55 from beneath the chute 54 and also to disengage the dog 69^a from the ratchet-wheel 63. Thus as soon as the pawl 64 is disengaged from the ratchet-wheel the spring 68 will cause the returning of said wheel to its initial position, where the pin 71 is in engagement with the seat 73. It is obvious, how- 120 125 130 135

ever, that with the parts so far described the lever 72 is held in position for disengaging the dog 69^a and coin-support 55 merely by the pin 71, and the latter is held in position 5 by the engagement of the pawl 64 with the ratchet-wheel 63. Thus before the pawl 64 is disengaged from the ratchet-wheel the lever 72, which is constantly acted upon by the spring 73, would be returned, and this would again engage the dog 69^a with the ratchet-wheel and lock the same from return movement. To prevent such a result, I provide means for temporarily locking the dog 69^a from reengagement, said means consisting in the dog or latch 76, secured to the lever 70. This dog or latch 76 extends adjacent to a lug 77 on the frame, and when the dog 69^a is disengaged from the ratchet-wheel the spring 78 will cause said latch 76 to engage with the lug 77. This will 15 serve to lock the dog 69^a from reengaging with the ratchet-wheel until after the pawl 64 is disengaged therefrom and the spring 68 has returned the wheel to its initial position. The latch 76 is then disengaged by the lug or 20 finger 79 on the bar 65, which in the return movement of said bar strikes against the latch 76 and disengages it from the lug 77. To prevent the possibility of the latch 76 being disengaged by the finger 79 before the pawl 25 30 35 40 45 50 55 60 65 69^a is disengaged from the ratchet-wheel, a cam 80 is arranged to engage with a lug 81 on the bar 65. This cam is preferably adjustably secured to the link 74 and is so positioned that the bar 65 in its downward movement will be moved laterally to disengage the pawl 64 at just the proper time. It is also preferably adjustably secured to the link 74 by means of screws 82 engaging with slotted bearings, thereby permitting of accurate setting. Means are also provided for retracting the pawl 64 from the ratchet-wheel 63 when the parts are in normal position, said means comprising a lever 83, fulcrumed upon the frame and connected by a link 84 to the bar 65. The opposite end of this lever has connected thereto a link 85, which is held by a spring 86 against a pin 87 on the cam 67. The link 85 has a shoulder 88 formed thereon, which in the normal position of parts is in engagement with the pin 87 and draws the lever 83 into a position where the pawl 64 is retracted from the ratchet-wheel 63.

As has been before stated, the metallic ribbon or strip which is to be embossed is fed 55 from the carriage 27 and between the rolls 25 and 26. The plane of feed extends between the wheels 1 and 2, so that the ribbon in its forward movement is passed between said wheels and in alignment with the registering dies. To prevent danger of the end of the ribbon catching upon either one or the other of the wheels 1 and 2, the normal plane of feed is at a point substantially midway between said wheels in their separated positions. The strip is preferably guided by a guide 89,

arranged just in rear of the wheels 1 and 2, said guide being slotted for the passage of the strip and flared on its rear side to receive the severed end of the strip. The guide 89 is normally in a position to hold the strip sufficiently below the wheel 1 to give ample clearance. When, however, the wheel 2 is operated and pressed against the wheel 1, the guide 89 is also raised. This is accomplished by a connection 90, extending downward and attached by a screw 91 to the traveling bearing 9. The movement of the guide just described is necessary by reason of the fact that the cutting-off male die, which is carried by the wheel 1, projects a short distance outward from the periphery of the wheel. Thus if the strip were fed in close proximity to the periphery of the wheel 1 it would interfere with the turning of said wheel to register the cutting-die with the strip, but with the construction shown clearance is provided for said die.

It is essential to the successful operation of the machine that the corresponding male and female dies be exactly registered before the embossing operation. The registration is effected, as before described, by moving the dial 21 into a position where the indicated character registers with the index 22; but in case the operator should carelessly fail to exactly register the character with the index the dies would not be properly registered. I have therefore provided means by which the dies are forced into exact registration before the embossing operation can take place and also means whereby the machine is locked from operation whenever the dial is stopped at an intermediate point between characters. For exactly registering the dies each of the wheels 1 and 2 is provided with an annular flange 92, having a series of slots 93 formed therein corresponding in number to the individual characters on the wheels. The carriage 27 is provided at its forward end with projecting fingers 94, said fingers tapering to a point and being adapted to enter the slots 93 whenever the wheels are in approximate registration. After the tapering points of the fingers 94 enter the slots they will operate as guides, which will turn the two wheels into exact registration. Should the wheels be in a position where the portion of the flanges 92 intermediate of the slots 93 registers with the fingers 94, and should the operator then attempt to actuate the machine, there would be danger of breaking the parts. This is prevented by an automatic lock, which is constructed as follows: The lever 50, which is used to actuate the carriage 27, is pivoted to the movable fulcrum 95. This fulcrum is itself pivoted to the frame 5 at a point 96, preferably slightly above the pivot 97 for the lever 50. The spring 98, secured to the arm 99 of the fulcrum member, serves to hold the latter normally in a position where a portion 100 there-

of is pressed against the frame 5. The tension of the spring 98 is sufficient to hold the parts in this position in normal operation of parts, so that the pivot 97 for the lever 50 remains stationary. When, however, the wheels 1 and 2 are out of registration and the fingers 94 strike against an intermediate portion of the flanges 92, the further movement of the cam 53 will cause a movement of the pivot 97, and consequently a rocking of the member 95 against the tension of the spring 98. The arm 99 of the member 95 has projecting therefrom a lug 101, which extends in adjacency to the arm 102 of the lever 103, fulcrumed upon the frame. The opposite end of this lever is of segmental form and has at one point thereon a detent 104. This detent in the normal position of parts is slightly below the path of the lug 62 on the arm 48, and therefore will not engage with said lug. As soon, however, as the member 95 has moved, as before described, the lug 101 thereon will actuate the lever 103 through its arm 102 and carry the detent 104 into the path of the lug 62. Thus further movement of said lug 62, and consequently of the rock-shaft 14 and parts actuated thereby, is prevented.

The general construction of parts being as described, the complete operation of the machine is as follows: The operator first drops a suitable coin through the slot into the conduit 54, through which it passes to the lower end thereof and rests upon the support 55. The handle 20 is then turned to register the first character which it is desired to emboss with the index 22. The operator next turns the crank-handle 24, which is free to move by reason of the fact that the coin in the chute 54 prevents the movement of the finger 57, and consequently through the mechanism previously described prevents the dog 60 from engaging with the lug 62. In the first part of the movement of the crank-handle the cam 53 will actuate the lever 50 to move the carriage 27 forward. At or near the completion of the forward movement of the carriage the lug 47 will engage with the lever 46 and actuate the latter, which, through the medium of the spring 49 and connecting-link 45, will operate the crank 39, which in turn will actuate the feed-wheels and also the lever 41 through the link 40. As soon as the lug 43 on the lever 41 engages with its corresponding stop 44 further movement of the disk is prevented. Thus in the operation so far described the carriage will have been moved forward and the strip fed upon said carriage an amount suitable for the character to be embossed. The next operation is the raising of the lower wheel 2, which is actuated by the antifriction - roll 15^a on the cam 15 engaging with the knuckle-joint of the toggle-lever, comprising the links 6 and 7. As the wheel is raised the guide 89 will be correspondingly moved through the connections

previously described, so that when the dies on the two wheels are pressed against the strip the latter will be held in exact position by the guide. Simultaneous with the operations which have been described the pawl 64 will be actuated through the mechanism before described and will turn the ratchet-wheel 63. This movement will be imparted to the shaft 38, which will turn the arm 69 against the tension of the spring 68 and will withdraw the pin 71 from its bearing against the lever 72. The handle 24 may then be returned, which is preferably automatically accomplished by a suitable spring, and its return is cushioned by suitable means, such as the dash-pot 105. Another character may then be selected and the operation repeated, and so on until the work is completed or until the limit is reached. This limit will occur, as has been previously described, whenever the ratchet-wheel 63 has completed a revolution and the pin 71 has operated with the lever 72 to retract the support 55 from beneath the coin-chute. As soon as this occurs the coin will drop out of the chute, and in the return movement of the handle 24 the ratchet-wheel 63 will be free, so as to permit the spring 68 to return it into its initial position—that is, where the pin 71 rests against the bearing 73. Just previous to this final operation the dog 106, carried by the rock-arm 69, will engage with the hammer 107 of a bell 108 and cause the ringing of said bell to indicate that the limit has been reached. If the operator desires to continue the operation, it will be necessary to insert a new coin into the conduit 54, which will again unlock the mechanism in the same manner as before. Whenever the desired number of characters have been embossed, the portion of the strip containing them may be severed from the main portion of the strip by male and female severing-dies carried by the wheels 1 and 2. The registration of these dies is indicated upon the dial in the same manner as the characters to be embossed, and whenever they are registered with the strip and the machine is operated the embossed portion will be cut off and dropped through a suitable chute leading out from the casing. Where a strip of considerable length is embossed, it is necessary to guide the projecting end so that it will not strike against the casing and prevent the further operation of the machine. This may be accomplished by a guide-roll 109, carried by a pivot-lever 110 and normally arranged in the front of the wheel 1, so that the work passing out therefrom will be deflected downward. The lever 110 has an arm which projects into proximity to the wheel 2 and into the path of the lug 111 and said wheel. This lug, whenever the cut-off dies are in registration, will actuate the lever 110, so as to lift the guide-roll 109. As soon, however, as the wheels are turned from this position the lug 111 will

disengage from the lever, and the guide-roll 109 will drop, thereby disengaging the severed strip in case it should cling to the die. The complete severance of the strip is also 5 facilitated by the retraction of the carriage after each embossing operation, which will partially withdraw the main portion of the strip, freeing it from the severing-die. Thus a strip having any number of characters 10 bossed thereon may be formed, it being only necessary to insert new coins whenever the limit of the machine is reached.

What I claim as my invention is—

1. In a machine of the character described, 15 the combination with a casing, of a pair of adjacent rotary heads arranged within the same, respectively provided with corresponding series of male and female dies, a shaft upon which one of said dies is mounted extending 20 outwardly through the casing, connecting-gearing between the head upon said shaft and the other rotary head, said latter head being supported in pivotal bearings, cam-actuated means operatively associated therewith where- 25 by the corresponding dies may be registered, a dial surrounding said first-mentioned shaft and visible from without the casing, and a co-operating index whereby the registered dies are indicated upon said dial.
- 30 2. In a machine of the character described, the combination with a pair of rotary heads provided with corresponding series of male and female dies, of means for correspondingly rotating said heads to register any selected 35 pair of dies, yieldable means for feeding the blank between said dies transversely to the plane of rotation, and means for pressing said dies together to operate upon said blank, after said feeding operation.
- 40 3. In a machine of the character described, the combination with a pair of rotary heads, provided with corresponding peripheral series of male and female dies, of a shaft upon which one of said heads is mounted, a pivotal bear- 45 ing for said shaft and a cam-actuated toggle-lever for rocking said pivotal bearing and pressing said heads together.
- 50 4. In a machine of the character described, the combination with a pair of rotary heads having corresponding series of peripheral male and female dies, a shaft upon which one of said heads is mounted, a pivotal bearing for said shaft, a toggle-lever connected to said pivotal bearing and a cam for pressing against 55 the knuckle of said toggle to straighten the latter and thereby press said heads together.
- 60 5. The combination with a casing of a pair of shafts therein arranged in a common plane, a rotary head on each shaft, said heads bearing peripheral series of corresponding male and female dies, a connecting-gearing between said shafts for causing a corresponding rotation thereof, an extension to one of said shafts passing out from said casing and having an 65 actuating - handle, a pivotal bearing for the
- other shaft, a toggle-lever for rocking said pivotal bearing to press said heads together, a rock-shaft having a cam thereon for bearing against the knuckle of said toggle, and an operating-handle for said rock-shaft arranged 70 without the casing.
6. In a machine of the character described, the combination with a pair of rotary heads having peripheral series of male and female dies, of means for feeding a blank between 75 said dies, means for correspondingly rotating said heads to register selected pairs of corresponding dies with said blank, a shaft upon which one of said heads is mounted, a pivotal bearing for said shaft, a toggle-lever for rocking said bearing to press said heads together and operate upon said blank, a cam for bearing against the knuckle of said toggle to actuate the same, and means for adjusting said toggle to vary the throw thereof. 80
7. In a machine of the character described, the combination with an inclosing casing, a pair of adjacent rotary heads arranged within the casing, respectively provided with corresponding male and female dies, shafts for the 90 heads, one of which extending without the casing, operating means upon said outwardly-extended portion of said shaft, cam-actuated means associated with the other shaft for actuating the corresponding dies, and a dial 95 visible from without the casing mounted upon said outwardly-extended shaft.
8. The combination with a pair of rotary heads carrying corresponding series of male and female dies, of means for correspondingly 100 rotating said heads to register selected pairs of dies, a reciprocating carriage for holding the blank and adapted to project the same between said dies, a common actuating means for first feeding said carriage forward and then 105 pressing said dies together, and means automatically actuated on the forward movement of said carriage for feeding forward the blank thereon.
9. In a machine of the character described, 110 the combination with a pair of relatively movable members having corresponding series of individually-registerable male and female dies, of means for pressing the dies together to operate upon the work, means automatically operating in advance of the latter movement for positioning said dies in exact registration when they have been previously approximately registered, and means operating when said dies are not in approximate registration for locking 115 the operating mechanism from further movement.
10. In a machine of the character described, 120 the combination with a pair of relatively movable members carrying corresponding series of individually-registerable male and female dies, of a work-holding carriage adapted for reciprocation toward or from said registered dies, and a guide-finger on said carriage adapted to move said members to exactly register 125 130

the dies when the latter are first approximately registered, means for first moving said carriage and for then pressing the said members together to cause the registered dies to operate upon the work, and means operating when said dies are not in approximate registration for locking the mechanism from movement.

11. In a machine of the character described, 10 the combination with a pair of rotary heads respectively provided with corresponding peripheral series of male and female dies, a reciprocatory carriage for holding the blank, adapted in its forward movement to project 15 said blank between said rotary heads, means for rotating said heads correspondingly to bring any selected pair of corresponding dies into approximate registration, slotted flanges upon said heads, guide-fingers upon said carriage for engaging with the slots in said flanges when said dies are in approximate registration, a common actuating means for first moving forward said carriage and then pressing said heads together, a yielding connection in 20 said carriage, operating mechanism, and means automatically operating by the striking of said fingers against said flanges, when said dies are not in approximate registration for locking said mechanism from further movement.
12. In a machine of the character described, 25 the combination with a pair of rotary dies having respectively corresponding peripheral series of male and female dies, a reciprocatory carriage for moving the blank between said rotary dies, a lever for reciprocating said carriage, a cam for actuating said lever a rock-shaft for operating said cam, means also operated by said rock-shaft for pressing said 30 heads together, a guide-finger on said carriage and a co-operating slotted guide-flange on said rotary head, a yielding fulcrum for said lever, and means actuated by the yielding of said fulcrum for locking said shaft from movement.
13. In a machine of the character described, 35 the combination with a rotary head having a series of peripheral dies, of a reciprocatory carriage, means on the carriage for feeding the blank across the periphery of said head during the forward movement of the carriage, means operatively associated with said last-mentioned means for causing the registered die to operate on said blank, a series of differential stops carried by said head and corresponding to said dies; said stops being adapted to respectively arrest the feed of said blank in advance of the operation of the die thereon, whereby the feed is proportioned to each die.
14. In a machine of the character described, 40 the combination with a rotary head having a series of peripheral dies thereon, of a carriage adapted to project the blank across the periphery of said head, blank-feed mechanism 45 on said carriage, means for first moving said

carriage toward said head and then causing the registered die to operate upon the blank, means for actuating the feed mechanism during the forward movement of said carriage and a series of differential stops carried by 70 said head adapted to respectively arrest the movement of said feed mechanism in advance of the operation of the registered die upon the blank.

15. In a machine of the character described, 75 the combination with a rotary head having a series of peripheral dies thereon, of a reciprocatory carriage adapted to project the blank across the periphery of said die, means for moving said carriage forward and then causing 80 the registered die to operate upon said blank, and means for retracting said carriage after the operation of said die.

16. In a machine of the character described, 85 the combination with a rotary head, having a series of peripheral dies thereon, of a reciprocatory carriage adapted to project the blank across the periphery of said head, means for feeding said carriage forward and then causing the registered die to operate upon said blank, 90 and means for then returning said carriage whereby the blank is drawn backward and disengaged from the die.

17. In a machine of the character described, 95 the combination with a rotary head having a series of peripheral embossing-dies thereon, and a cut-off die, of a reciprocatory carriage adapted to project the blank across the periphery of said head, means for first moving said carriage forward and then causing the registered die to operate upon the blank, and means for then returning said carriage whereby the blank is drawn back to disengage it from the embossing-dies or to separate the severed and unsevered portions of the blank when operated upon by the cut-off die.

18. In a machine of the character described, 100 the combination with a rotary head having a series of peripheral dies thereon, of a reciprocatory carriage adapted to project the blank across the periphery of said head, a blank-feeding roll on said carriage, means for first moving said carriage forward and then causing the registered die to operate upon the blank, means for rotating said feed-roll during the forward movement of said carriage to advance the blank in relation thereto, and a series of differential stops carried by said head and corresponding to said dies, said stops being respectively adapted to arrest the movement of said feed-roll in advance of the operation of the die for the purpose described.

19. In a machine of the character described, 105 the combination with a rotary head having a series of peripheral embossing-dies, and a cut-off die, of a reciprocatory carriage adapted to project the blank across the periphery of said head, blank-feeding mechanism upon said carriage, means for first moving said carriage forward, and then causing the registered die 110

- to operate upon the blank, means for actuating the feed mechanism during the forward movement of said carriage, and a series of differential stops, carried by said head, corresponding to said embossing-dies and respectively adapted to arrest the feeding of the blank before the completion of its movement, and in advance of the operation of the die thereon, whereby a greater feed is imparted to the blank when registered with the cut-off die.
20. In a machine of the character described, the combination with a rotary head having a series of peripheral dies thereon, and a laterally-projecting slotted annular flange, of a reciprocatory carriage adapted to project the blank across the periphery of said head, a guide-finger on said carriage adapted to engage with one of the slots in said annular flange when the corresponding die is in approximate registration with the blank; mechanism for first feeding said carriage forward and then causing the die to operate upon the blank, a yielding member in said mechanism for permitting the arrest of said carriage when said guide-finger contacts with the imperforate portion of said annular flange, and a lock for said mechanism adapted to be automatically operated upon the yielding of said member.
30. 21. In a machine of the character described the combination with a rotary head having a series of peripheral dies thereon, of a reciprocatory carriage adapted to project the blank across the periphery of said head, a blank-feeding roll upon said carriage, an actuating-crank for said roll, a link adapted to move transversely of the movement of said carriage and connected to said crank, and mechanism for first causing the forward movement of said carriage, and subsequently the operation of the registered die upon said blank, said mechanism also causing the movement of said link during the movement of said carriage whereby the blank is advanced thereon.
45. 22. In a machine of the character described, the combination with a rotary head having a series of peripheral dies thereon, of a reciprocatory carriage adapted to project the blank across the periphery of said head; a blank-feeding roll on said carriage, an actuating-crank therefor, a link secured to said crank and extending transversely of the direction of

movement of said carriage, a stop-rod secured to said crank and projecting into proximity to said rotary head, a series of differential stops carried by said head and corresponding to said dies, said stops being respectively adapted to extend into the path of said stop-rod, and mechanism for simultaneously feeding the said carriage forward, and yieldingly operating said link, and for subsequently causing said die to operate upon the link whereby the feeding of the blank is arrested in proportion to the requirement of each die and before the operation thereon.

23. In a machine of the character described, the combination with a pair of rotary heads, provided with corresponding peripheral series of male and female dies, a pivotal bearing for one of said dies, and an extensible toggle-lever for rocking said pivotal bearing and pressing said dies together, and means for retaining said lever in adjusted positions.

24. In a machine of the character described, the combination with a pair of rotary heads, provided with corresponding peripheral series of male and female dies, a pivotal bearing for one of said dies, a toggle-lever, and a cam operatively associated with the knuckle-joint of said lever for contacting the dies.

25. In a machine of the character described, the combination with a pair of rotary heads, provided with corresponding peripheral series of male and female dies, shafts upon which said heads are respectively mounted, connecting-gearing for causing a corresponding movement of said shafts and heads, a toggle-lever operatively associated with one of said shafts and cam-actuating means associated with the latter.

26. In a machine of the character described, the combination with a pair of rotary heads arranged above one another, the upper one being stationary, a shaft, and an upwardly-extended pivotal bearing on the shaft associated with the lower head, and cam-actuated means operatively associated with said bearing.

In testimony whereof I affix my signature in presence of two witnesses.

AUGUSTE ARTHUR CAILLE.
